Specification of Letters Patent.

Patented June 1, 1920.

Application filed December 1, 1919. Serial No. 341,567.

To all whom it may concern:

Be it known that I, FRANK MONGIN DE SAUSSURE, Jr., a citizen of the United States, and a resident of Greenville, in the 5 county of Greenville and State of South Carolina, have invented certain new and useful Improvements in Ladders, of which the following is a specification.

My present invention relates generally to 10 ladders and more particularly to folding ladders especially those in which the side rails are swingable by virtue of pivoted rungs toward and away from one another, one object among others being the provision 15 of means automatically acting in connection with a supporting surface whereby to lock the side rails of the ladder section in non-shiftable relation when engaged with a supporting surface either in a horizontal line 20 or upon more or less of an incline.

Other objects relating for the most part to minor structural details as well as the resulting advantages of my invention will appear in the course of the following description, 25 reference being made to the accompanying drawings, which form a part of this specification and in which:

Figure 1 is a rear elevation with the parts in extended operative position,

Fig. 2 is a side elevation of the parts folded,

Fig. 3 is a horizontal section through the ladder portion,

Fig. 4 is a longitudinal section there- 35 through,

Fig. 5 is a detail perspective view of one of the side braces connecting the ladder and prop sections,

Fig. 6 is a side elevation of the complete 40 ladder in the open position,

Fig. 7 is an elevation of the lower end of the ladder section,

Fig. 8 is a vertical section taken through one side rail of the ladder section on line 45 8—8 of Fig. 7, and

Fig. 9 is a view similar to Fig. 7, with the parts in partly folded position.

Referring now to these figures, my present invention as in certain applications previously filed by me, includes a ladder section 50 10 and a prop section 11, particular reference being made to Fig. 6 from which the relation of these two sections will most plainly appear.

The prop section includes side legs 12 whose upper ends are pivoted in brackets 13

secured upon the rear faces of the side rails 14 of the ladder section, as best seen in Fig. 1, from which it will be noted that the brackets 13 are secured upon slight inclines 60 so that the lower free ends of the legs 12 may be adjustably set apart within certain limits, by means of a two part adjustable transverse bracket 15, between the lower portions of the side legs the parts of which 65 are slotted for the reception of a securing bolt and nut 16.

To the upper portions of the side legs 12 are pivoted the upper ends 17 of crossed pivoted braces 18 whose lower pivots 19 70 run in slots 20 at the lower free ends of the legs, so that the legs are thus adapted to pivot in the brackets 13 toward and away from the ladder section and are also adapted, by virtue of the particular connection of 75 braces 18, for movement toward and away from one another.

The slide rails 14 of the ladder section 10 have inner lengthwise grooved faces as best seen in Figs. 3 and 4, and within their 80 grooves 21 the ends of the rungs 22 are pivoted, the upper rung 22^a, as seen by a comparison of Figs. 1 and 2 being intermediately connected to and rigid with the top step 23.

Thus the side rails 14 are swingable into and out of the folded position shown in Fig. 2 upon the pivoted connections of the rungs 22, and it is obvious that they are shiftable in the same manner with respect to one another in order that their lower ends may uniformly engage an uneven or inclined supporting surface.

It is obvious, however, that some means must be provided to avoid danger of this 95 collapsible or folding movement of the structure when the latter is in use and for the purpose of providing a quick automatically acting arrangement, I utilize a locking structure shown particularly in 100 Figs. 6 to 9 inclusive, in connection with the lower portions of the side rails 14 of the ladder section 10, preferably upon the rear surfaces of these rails so as to avoid all danger of interfering with the operator 105 or user.

This locking arrangement includes a lengthwise slotted locking plate 24 whose longitudinal slot shows plainly at 25 in Fig. 9, and whose upper offset end is rigidly secured to the rear face of one of the side rails 14 and whose lower angular end 26 is

similarly secured to the lower end of the leg 14 so as to thus hold the body of the plate in slightly spaced relation with respect to the side rail. Extending outwardly from 5 the lower portion of the locking plate 24, is a stud 27 which projects through the longitudinal slot 28 of a sliding latch plate 29, the lower end of this latch plate being adapted for engagement with a supporting 10 surface and the upper end thereof having a stud 30 which is also slidable in the slot 25 of the lock plate 24.

The upper end of the latch plate 29 is also cut away on an angle and its angular 15 end surface 31 has teeth for engagement with the toothed portion 32 of the lower edge of a lever 33. This toothed lower edge of lever 33 is formed adjacent to one end thereof which carries a pivot pin 34 slidable 20 in the lengthwise slot 25 of the locking plate 24 between the upper toothed end 31 of the latch plate and a locking piece 35 having a clamping bolt and nut 36 extending through the slot 25 of the locking plate and slidable 25 therein when loosened. This locking piece 35 has a toothed surface 37 engageable with the upper angular toothed edge 38 of lever 33 adjacent to its pivot 34, the opposite end of this lever 33 being pivoted at 39 to the 30 other rail 14 of the ladder section so as to extend at an angle when the side rails 14 are in their spaced apart effective position.

The latch plate 29 is freely slidable so that by suddenly elevating the respective 35 side rail 14 of the ladder section, the latch plate, whose lower end in the uppermost position depends slightly below the lower end of the respective side rail, will slide downwardly free from engagement with the lever 33 and thus permit the toothed end of 40 this lever to drop away from the locking piece 35. In this way, upward movement of the side rail 14 to which the locking plate 24 is secured, may be continued if it is desired to fold the side rails against one another.

Normally with the side rails 14 in engaged 50 relation upon an even supporting surface, the parts assume the position of Fig. 7, latch plate 29 being forced upwardly against the toothed end of lever 33 so as to effectively lock the same between the latch plate and the latch piece 35.

It is obvious this same function may be 55 served by the parts for one side rail to which the locking plate 24 is secured if elevated above the other side rail upon an uneven or inclined supporting surface and that if it is desired to secure the parts in 60 locked or braced position with one of the side rails above the level of the other, the locking piece 35 may be dropped in the slot 25 of the locking plate 24 and secured by its bolt and screw 36 in proper relation to the 65 other adjusted parts.

In Fig. 5, I have shown one of the transverse braces 40 between the ladder and prop sections, this brace being in two sections pivotally connected at 41 and one of which has a lug 42 engaging the other in open 70 position. One end of this brace 40 is preferably offset as at 43 and pivotally connected to the respective side leg 12 of the prop section 11, the opposite end of the brace being pivotally connected upon a bolt 75 44 at the side of the respective ladder rail 14 with a small spring 45 interposed between the same and the head of the bolt to avoid rattling.

It is to be plainly seen in Fig. 3 that the 80 opposite offset end of each brace is connected to the prop section, and it is thus obvious the prop section is freely movable upon its pivots in the brackets 13 toward and away from the ladder section, either 85 with or without greater spread of its lower free ends than their normal spreading by the adjustment of the pivoted lateral brace 15, 15.

When in the folded or collapsed position 90 shown in Fig. 2, the prop and ladder sections are latched by means of a spring latch plate 46 seen clearly in Fig. 2, whose extending portion has an opening for the reception of a pin 47 projecting laterally from one of the side rails 14 of the ladder section, so that in its folded or collapsible position, the complete ladder may be carried by the user from place to place without the necessity of a grasp upon both the ladder 100 section and the prop section to keep these sections from swinging apart.

It is obvious that my present invention thus provides considerable improvement over the usual foldable or collapsing step 105 ladder and special attention is called to the automatically acting means engageable with a supporting surface to lock the rails of the ladder section against relative swinging movement, when once placed in uniform 110 engagement upon an uneven or inclined surface.

Attention is also called to the type of this locking device whereby it may be shaken free by quick lifting of one of the side rails 115 so that without bothering to loosen set screws, nuts and the like, the ladder section with the prop section may be readily folded and collapsed.

I claim:

1. A ladder of the character described, including side rails, rungs pivotally connected to the side rails to permit the latter to swing toward and away from one another in parallel relation, and connections between the side rails for securing the same in various spaced positions between full open and closed positions.

2. A ladder of the character described, including side rails, rungs pivotally con- 130

- nected to the side rails to permit the latter to swing toward and away from one another in parallel relation, and connections between the side rails for securing the same in various spaced positions between full open and closed positions, said means including a controlling latch shiftable into and out of effective position upon engagement with and removal from a supporting surface.
- 10 3. A ladder of the character described, comprising side rails, rungs pivotally connecting the side rails for swinging movement toward and away from one another, a lever having pivotal connection at its opposite end with the side rails and a sliding latch on one of the said rails freely movable into and out of engagement with one end of the lever and arranged to extend at one end beyond the respective ground engaging end of its side rail.
- 15 4. A ladder comprising side rails, rungs pivotally connected to the side rails, a lever pivotally connected at one end to one of the side rails, and having upper and lower toothed edges at its opposite end, a slotted plate secured to the other side rail and through the slot of which the toothed end of the lever has a running pivot, a toothed locking piece, slidable with respect to the locking plate above the lever, and a latch plate having sliding connection through the slot of the locking plate below the toothed lever, said latch plate having an upper toothed end and having its lower end projecting beyond the respective ground engaging end of its side rail as described.
- 20 5. A ladder of the character described, comprising side rails, rungs pivoted to the side rails, a locking plate on one of the side rails, a lever pivoted at one end to the locking plate and at its opposite end to the other side rail, a latch plate slidable with respect to the locking plate below the lever and a locking piece slidable with respect to the locking plate above the lever, the said lever, said latch plate and said locking piece having relatively engaging toothed portions, as described.
- 25 6. A ladder of the character described, comprising side rails, rungs pivoted to the side rails, a locking plate on one of the side rails, a lever pivoted at one end to the locking plate and at its opposite end to the other side rail, a latch plate slidable with respect to the locking plate below the lever and a locking piece slidable with respect to the locking plate above the lever, the said lever, said latch plate and said locking piece having relatively engaging toothed portions, as described.
- 30 7. A ladder of the character described, comprising side rails, rungs pivoted to the side rails, a locking plate on one of the side rails, a lever pivoted at one end to the locking plate and at its opposite end to the other side rail, a latch plate slidable with respect to the locking plate below the lever and a locking piece slidable with respect to the locking plate above the lever, one end of said latch plate projecting beyond the respective ground engaging end of its side rail and means for adjustably securing the locking piece on the locking plate, as described.
- 35 8. A device of the character described, including a ladder section, having side rails, a prop section having side legs, brackets secured lengthwise of the rear faces of the side rails of the ladder section within which the side legs of the prop section are pivoted adjacent to one end, and an adjustable lateral brace between the side legs of the prop section adjacent to their opposite ends and at right angles thereto, said brackets being inclined with respect to the longitudinal axes of the side rails of the ladder section to permit of adjustably spreading the braced ends of the side legs.
